UNITED STATES PATENT OFFICE

2,568,010

PROCESS FOR THE PRODUCTION OF A LINING FOR PRESSURE GALLERIES AND SHAFTS

Alois Kieser, Bregenz, Austria

Application May 7, 1947, Serial No. 746,476
In Germany July 27, 1943Section 1, Public Law 690, August 8, 1946
Patent expires July 27, 1963

8 Claims. (Cl. 61—45)

1

Various processes have been proposed already to prevent the formation of cracks in the lining of pressure tunnels, pressure shafts and other structures subjected to high operating pressure, in which processes the lining is to be placed under such an initial pressure, by means of pressed concrete, that the compressive stress caused thereby in the lining exceeds the tensile stress caused by the operating pressure. With these known processes, however, the required initial pressure cannot be achieved, partly because they suffer from structural faults and partly because they do not fulfill the theoretical conditions. All known processes have this common feature that the pressed concrete is introduced directly into the hollow space between the rock surface and an expandable shell or an inner core ring formed of concrete or shaped blocks. Such a cross sectional structure, however, suffers from the drawback that it hinders the appropriate installing of the shell or the inner core ring, above all in "ravelly" rock. Moreover, the hollow space to be filled with backing-up material greatly varies in thickness owing to the irregular tunnel bore so that, apart from a high consumption in expansive pressed mortar, the initial pressure is impaired by the shrinkage of the comparatively thick and irregular mortar ring. Moreover, the known processes do not provide for actually holding the pressure required for the initial pressure at the correct level until the pressed mortar has hardened.

The drawbacks that are only briefly indicated above, are avoided according to the invention in that an outer lining ring adjacent to the surrounding rock and an inner core ring are provided, leaving an annular space between both rings, and that the core ring is placed under an initial pressure by pressing a filling and sealing mass into the hollow space formed between the core and lining rings in order to effectively prevent the formation of cracks in the core ring and thus to prevent water losses, when the tunnel tubes are subjected to pressure.

For this purpose it is possible either to provide for a spacing insertion of corrugated iron between the core and lining rings or to wall up the core ring of shaped blocks of concrete or another suitable building material so that the hollow space between the core and lining rings is provided, e. g. by the special structure of the outside surface of the shaped blocks.

Annular partitioning and sealing elements, perpendicular to the tunnel axis, are provided in said annular space, for subdividing said space

2

into separate zones, which are successively filled with a material which is allowed to harden under pressure.

In the drawing the object of the invention is exemplified with reference to two modes of execution, Fig. 1 illustrating a pressure gallery in cross-section according to the first mode at the left without and at the right with a "Torkret" collar, whilst Fig. 2 is a longitudinal section of same, 10 and Fig. 3 the medium top or crest part of Fig. 2, on an enlarged scale. Fig. 4 is a section taken in the line A—A of Fig. 3, Fig. 5 illustrates a crest cross-section through the second mode of execution of the pressure gallery wherein the section 15 on the left half of the figure is taken on the line F—F of Fig. 6 within the range of the "Torkret" collar, and on the right half of the figure outside of said range. In contradistinction thereto the left part of Fig. 6 relates to a section along 20 the line B—B displaced into the crest plane, whilst the right hand part of this figure is a section taken along the line C—C of Fig. 5. Finally Fig. 7 is a moulded or profiled brick as required, seen from above, whereas the Fig. 8 is a section 25 taken on the line D—D, and Fig. 9 a section taken along the line E—E of Fig. 7. Fig. 10 is a perspective view of a molded zone edge block used in the core ring.

With both modes of execution a lining *b* is 30 produced adjacent to the rock *a*. The concrete utilized for same need not be of a high grade. In solid rocks a minimum thickness of 10—15 cm. will suffice, whilst if the rock is not rigid the lining ring will have to resist the pressure of the soil, and must accordingly be of adequate thickness. The lining ring *b* can be made of concrete in the usual manner. It is economically advantageous to employ a portable scaffolding fitted with iron shuttering (boarding), the concrete being introduced according to the pumping process. 40 The latter is also advisable as it permits to reduce the thickness of the lining, and consequently the volume of rock to be broken out.

According to the first mode of execution as 45 illustrated in the Figures 1—4 the lining ring *b* encloses an annular hollow *c* with corrugated iron insets, as customary in trade, made from black sheet, or for barring out iron as constructing material, with corrugated plates made of 50 "Eternit" (artificial slate), or any other suitable substitute. A special design of the corrugated inset e. g. in semicircular shape fitted with ribs perpendicularly located in respect to the gallery axis would considerably simplify the insertion. 55 The individual parts of the corrugated insets are

laid without joint tightening in such a manner as to overlap on all sides, and are fastened to the curved wall surfaces, so that they are prevented from detaching or separating. With the ribs located transversely the stiffness will facilitate the insertion and the fixation; on the other hand in this case an inset must be used rounded according to the inner diameter of the lining ring *b*.

On the walls, and at the tunnel crest more points of fixation are required than on the floor or bottom. The longitudinal and transversal joints need not be tightened as it is desirous that a portion of the packing mass should penetrate between the corrugated inset and the core ring for filling hollows, if any, and for increasing the density of said ring. If necessary, this process may be furthered by boring additional holes into the corrugated inset.

According to the first mode of execution a core ring *e* made of concrete is arranged within the corrugated inset *d*, the concrete having to be of adequate strength and density. For introducing the concrete any of the methods hitherto used may be employed. The fact that the outer curved wall of the tunnel is not formed by the rocks, but by the lining ring filled with the corrugated inset facilitates the irreproachable production of a high grade concrete for the core ring calculated in conformity with the principles of statics. Special economic advantages are realized by introducing the concrete in one casting operation according to the pumping process.

At certain intervals tightening rings *h* are provided contiguous to the lining ring *b* and corresponding to the height of the corrugated insert. These rings are produced by groove-shaped recesses in the shuttering (boarding) provided in the course of making the concrete lining ring. These tightening rings close the hollows *c* so as to create zones separated from each other.

In the concrete of the core ring *e* the filling and pressure gauging tubes (pipes) *f* are embedded connecting the interior of the core ring with each zone of the hollow *c*.

Opposite to the filling tubes (pipes) *f* filling grooves *g* are provided in each zone in the lining ring *b*. Besides recesses are left open in suitable distances in the lining ring *b* so as to warrant the mobility of the packing masses perpendicularly to the ribs of the corrugated inset because of the ribs considerably narrowing the cross-section of flow in this direction.

With both modes of execution bore-holes *i* are provided leading through the lining ring *b* into the rock *a*. Besides a draining pipe *k* is laid in the lower part of the ring which may be closed by a gate valve *l*.

According to the second mode of execution the core ring is composed of moulded or profilated bricks *m* made of concrete or any other suitable building material, and located close to the lining ring *b*. With the exception of the crown no corrugated insets are employed whereas in their stead the outer faces of the moulded or profilated bricks are furnished with undulatory ribs *n*. The mortar joints in the planes perpendicular to the ring axis are formed into wedge joints *o* for self-tightening under inner pressure. The axial joints *o'* are also filled with mortar. The tightening in respect to the neighbouring zones is effected by the insertion of zone-margin bricks *p*, the projections *p'* of which will contact the lining ring *b* along the zone margin without leaving any gaps, so that with this mode of design the tight-

ening rings *h* which are necessary with a core ring made into a self-contained piece of concrete as per the first process, can be dispensed with. Also the grooves *g* in the outer lining located perpendicularly to the corrugated ribs may be done away with, considering that the mobility of the packing masses in this direction may be secured by appropriate recesses in the moulded or profilated bricks. In each zone special blocks are provided to contain the filling- and the pressure gauging tubes (pipes) *f*. The use of moulded bricks not only renders superfluous the distance insets, but at the same time facilitates the construction of the core ring closely adjoining the lining ring. A scaffolding is only required for the vaults which consequently are not started building before the lower half of the core ring is completed. For warranting the right distance being kept in regard to the lining ring *b* the crown *g* of the core ring is furnished with a corrugated iron inset *d* with concrete or pressed mortar.

The initial pressure in the core ring is brought about by pressing the necessary quantity of material into the hollows *c* and the chambers, bores, grooves, cracks, etc. adjoining which process may rightly be called the "packing" of the core ring. For this purpose the packing or filling is carried out by zones by way of simultaneously utilizing all filling tubes (pipes) *f* of one zone while checking the initial or preliminary pressure actually attained in the packing ring. It is advisable to employ packing masses having hydraulic qualities such as are capable of setting and hardening. In this case the pressure conditions existing at the time of setting are maintained unaltered after hardening provided that no change of temperature occurs. An appropriate filling having hydraulic properties is e. g. a cement-sand-water mixture of the actually most favourable mixing ratio. This filling mass renders necessary a subdivision of the packing process into five individual phases, viz.

1 phase.—For thoroughly moistening the hollows water is, at short intervals, pumped into under moderate pressure, and then drained off again.

2 phase.—Coarse filling mortar is introduced up to saturation equally under a moderate pressure.

3 phase.—Without reducing the pressure the filling device is switched over to fine mortar, and later on to cement milk, whereby the pressure is gradually increased up to the maximum pressure desired.

4 phase.—Before the packing mass starts setting the filling device is switched over to water, also without reducing the pressure and continues to operate in this manner until the packing mass has completely set and has sufficiently hardened, so as to warrant the initial compressive stress of the core ring as required.

5 phase.—High pressure filling and packing by means of cement milk or any other appropriate tightening means. This phase follows phase 4 at a certain interval, and is intended to fill hollows left empty by the pressing water in connection to the filling tubes (pipes) in the packing chamber.

If the initial pressure need not be mentioned at its full value it is also possible to employ masses having no hydraulic properties such as bitumen, loam, and the like. In this case a sufficient preliminary tension is only maintained if the filler

is prevented from gradually escaping under the initial pressure, and in particular if the filling and pressure gauging tubes (pipes) are carefully closed.

The packing process described warrants a sufficient static security against a high inner pressure or against an outer pressure, if any, eventually occurring with the gallery tube discharged. The core ring is in this case imparted an initial pressure preventing the formation of tensile strains and, consequently, cracks under the action of the service pressure. In the course of the packing operation it is desirable that cracks and fissures should be formed in the concrete mass of the outer ring as shown in Figs. 5-8 so as to open the way for the packing as far as possible into the clefts and crevices of the surrounding rocks. For accelerating the flow of the mortar into the hollows outside of the lining ring *b* the holes *i* are used which are bored into the rocks through the concrete layer.

The packing process described transforms the entire envelope of the core ring into a tightly compressed mass in which the fragments of the outer lining ring after its rupture are solidly cemented to the core ring by means of the packing.

For example a tunnel may have an interior diameter of the inner ring *i. e.* of the tunnel tube proper of 2.40 m. an outer diameter of 2.80 corresponding to a ring thickness of 20 cm. and an initial pressure of 100 m. water column, yielding annular compressive strains of 70 kg./cm.² so that at the cube strength of 280 kg./cm.² a factor of safety results amounting to 4 (on basis of an approximate calculation using the simple ring formula, and neglecting both the proper weight of the ring and the pressure difference between the floor and the crown). Without setting up tensile strains in the core this gallery may be loaded interiorly with a water pressure of

$$116 \text{ m. } \left(= 100 \frac{280}{240} \right)$$

In all cases in which the initial pressure desired cannot be attained during the packing phase 3 owing to the numerous clefts of the rocks, or cannot be maintained at the level desired so that great losses of water escaping into the rocks cannot be avoided during phase 4, a reinforced Torkret collar *r* must be inserted, whereby the dimensions of the reinforcing organs *s* are determined unequivocally by the difference of pressure between the initial pressure actually attained in the course of phase 3, and ascertained by means of pressure verifiers and the initial pressure desired. The lacking initial pressure per unity of length equal to the pressure difference multiplied by the outer core ring diameter is to be eeked out by the iron tensile force of the collar per unity of length. As iron will—on principle—only be inserted in those zones in which the lining cannot be given the necessary safety in any other manner, and as the dimensions of the reinforcements *s* will depend on the actual requirements, a great economy in the use of iron is warranted by the method described.

If a tunnel executed in conformity with the second mode of construction according to the Figs. 5-9 requires smooth walls for hydraulical reasons an appropriate plaster *t* will be applied to the inner walls of the tunnel.

Apart from the pressure tunnels passing through rocks the process described may be used

for all diameters occurring in hydraulic plants, including oblique and vertical pressure shafts.

What I claim is:

5. A lining for pressure tunnels, comprising an inner core ring, an annular space enclosing said core ring and filled with a backing up material under initial pressure for exercising on said core ring an initial compressive stress, an outer lining ring between said annular space and the surrounding rock, annular partitioning and sealing elements perpendicular to the tunnel axis in said annular space, for subdividing said space into separate zones, and elements for spacing the core ring from the lining ring at a plurality of points in each zone.
10. 2. A lining for pressure tunnels, comprising an inner core ring, an annular space enclosing said core ring and filled with a backing up material under initial pressure for exercising on said core ring an initial compressive stress, an outer lining ring between said annular space and the surrounding rock, annular partitioning and sealing elements perpendicular to the tunnel axis in said annular space, for subdividing said space into separate zones, and elements for spacing the core ring from the lining ring at a plurality of points in each zone, and tubes inserted through said core ring and communicating with each zone of said annular space.
15. 3. A lining for pressure tunnels, comprising an inner core ring, an annular space enclosing said core ring and filled with a backing up material under initial pressure for exercising on said core ring an initial compressive stress, an outer lining ring between said annular space and the surrounding rock, annular partitioning and sealing elements perpendicular to the tunnel axis in said annular space, for subdividing said space into separate zones, elements for spacing the core ring from the lining ring at a plurality of points in each zone of said annular space.
20. 4. A lining for pressure tunnels, comprising an inner core ring, an annular space enclosing said core ring and filled with a backing up material under initial pressure for exercising on said core ring an initial compressive stress, an outer lining ring between said annular space and the surrounding rock, annular partitioning and sealing elements perpendicular to the tunnel axis in said annular space, for subdividing said space into separate zones, elements for spacing the core ring from the lining ring at a plurality of points in each zone, and grooves on the inside surface of said lining ring in each zone of said annular space.
25. 5. A lining for pressure tunnels, comprising an inner core ring, an annular space enclosing said core ring and filled with a backing up material under initial pressure for exercising on said core ring an initial compressive stress, an outer lining ring between said annular space and the surrounding rock, annular partitioning and sealing elements perpendicular to the tunnel axis in said annular space, for subdividing said space into separate zones, and corrugated iron sheets for spacing the core ring from the lining ring at a plurality of points in each zone.
30. 6. A lining for pressure tunnels, comprising an inner core ring which comprises molded blocks having protrusions on their outside surface, an annular space enclosing said core ring and filled with a backing up material under initial pressure for exercising on said core ring an initial compressive stress, an outer lining ring between said annular space and the surrounding rock, said protrusions of the molded blocks of the core ring spacing the lining ring from the core ring, and annular partitioning and sealing elements perpendicular to the tunnel axis in said annular space, for subdividing said space into separate zones.
35. 7. A lining for pressure tunnels, comprising an inner core ring which comprises molded blocks having protrusions on their outside surface, an annular space enclosing said core ring and filled with a backing up material under initial pressure for exercising on said core ring an initial compressive stress, an outer lining ring between said annular space and the surrounding rock, said protrusions of the molded blocks of the core ring spacing the lining ring from the core ring, and annular partitioning and sealing elements perpendicular to the tunnel axis in said annular space, for subdividing said space into separate zones.
40. 8. A lining for pressure tunnels, comprising an inner core ring which comprises molded blocks having protrusions on their outside surface, an annular space enclosing said core ring and filled with a backing up material under initial pressure for exercising on said core ring an initial compressive stress, an outer lining ring between said annular space and the surrounding rock, said protrusions of the molded blocks of the core ring spacing the lining ring from the core ring, and annular partitioning and sealing elements perpendicular to the tunnel axis in said annular space, for subdividing said space into separate zones.
45. 9. A lining for pressure tunnels, comprising an inner core ring which comprises molded blocks having protrusions on their outside surface, an annular space enclosing said core ring and filled with a backing up material under initial pressure for exercising on said core ring an initial compressive stress, an outer lining ring between said annular space and the surrounding rock, said protrusions of the molded blocks of the core ring spacing the lining ring from the core ring, and annular partitioning and sealing elements perpendicular to the tunnel axis in said annular space, for subdividing said space into separate zones.
50. 10. A lining for pressure tunnels, comprising an inner core ring which comprises molded blocks having protrusions on their outside surface, an annular space enclosing said core ring and filled with a backing up material under initial pressure for exercising on said core ring an initial compressive stress, an outer lining ring between said annular space and the surrounding rock, said protrusions of the molded blocks of the core ring spacing the lining ring from the core ring, and annular partitioning and sealing elements perpendicular to the tunnel axis in said annular space, for subdividing said space into separate zones.
55. 11. A lining for pressure tunnels, comprising an inner core ring which comprises molded blocks having protrusions on their outside surface, an annular space enclosing said core ring and filled with a backing up material under initial pressure for exercising on said core ring an initial compressive stress, an outer lining ring between said annular space and the surrounding rock, said protrusions of the molded blocks of the core ring spacing the lining ring from the core ring, and annular partitioning and sealing elements perpendicular to the tunnel axis in said annular space, for subdividing said space into separate zones.
60. 12. A lining for pressure tunnels, comprising an inner core ring which comprises molded blocks having protrusions on their outside surface, an annular space enclosing said core ring and filled with a backing up material under initial pressure for exercising on said core ring an initial compressive stress, an outer lining ring between said annular space and the surrounding rock, said protrusions of the molded blocks of the core ring spacing the lining ring from the core ring, and annular partitioning and sealing elements perpendicular to the tunnel axis in said annular space, for subdividing said space into separate zones.
65. 13. A lining for pressure tunnels, comprising an inner core ring which comprises molded blocks having protrusions on their outside surface, an annular space enclosing said core ring and filled with a backing up material under initial pressure for exercising on said core ring an initial compressive stress, an outer lining ring between said annular space and the surrounding rock, said protrusions of the molded blocks of the core ring spacing the lining ring from the core ring, and annular partitioning and sealing elements perpendicular to the tunnel axis in said annular space, for subdividing said space into separate zones.
70. 14. A lining for pressure tunnels, comprising an inner core ring which comprises molded blocks having protrusions on their outside surface, an annular space enclosing said core ring and filled with a backing up material under initial pressure for exercising on said core ring an initial compressive stress, an outer lining ring between said annular space and the surrounding rock, said protrusions of the molded blocks of the core ring spacing the lining ring from the core ring, and annular partitioning and sealing elements perpendicular to the tunnel axis in said annular space, for subdividing said space into separate zones.

pressive stress, an outer lining ring between said annular space and the surrounding rock, said protrusions of the molded blocks of the core ring spacing the lining ring from the core ring at a plurality of points in each zone, and annular partitioning and sealing elements perpendicular to the tunnel axis in said annular space for subdividing said space into separate zones, said annular partitioning and sealing elements being composed of zone edge blocks of the core ring having special protrusions.

7. A process for constructing a lining for pressure tunnels, comprising the steps of covering the rock surface of the tunnel with a lining ring, constructing an inner core ring so as to leave between said rings an annular space, providing in said annular space elements perpendicular to the tunnel axis for subdividing said space into zones which are tightly separated from each other, filling each zone with a liquid backing up material, and pressurizing said backing up material while allowing it to harden so that the hardened backing up material exercises on said core ring an initial compressive stress.

8. A process for constructing a lining for pressure tunnels, comprising the steps of covering the rock surface of the tunnel with a lining ring, constructing an inner core ring so as to leave be-

tween said rings an annular space, providing in said annular space elements perpendicular to the tunnel axis for subdividing said space into zones which are tightly separated from each other, filling each zone with a liquid backing up material until a predetermined pressure has been reached, interrupting the flow of the backing up material, and hydraulically pressurizing said backing up material while allowing it to harden so that the hardening backing up material exercises on said core ring an initial compressive stress.
